UNITED STATES PATENT OFFICE.

CHARLES A. ARMANTROUT, OF SEYMOUR, IOWA.

AUTOMATIC AND REVERSIBLE SHEET-METAL WEATHER-STRIP FOR DOORS.

SPECIFICATION forming part of Letters Patent No. 686,244, dated November 12, 1901.

Application filed July 29, 1901. Serial No. 70,118. (No model.)

To all whom it may concern:

Be it known that I, CHARLES A. ARMANTROUT, a citizen of the United States, residing at Seymour, in the county of Wayne and State of Iowa, have invented a new and useful Automatic and Reversible Sheet-Metal Weather-Strip for Doors, of which the following is a specification.

My object is to improve the construction, durability, and efficiency of the automatic weather-strip for doors for which Patent No. 653,606 was granted to me July 10, 1900, by making all its parts of metal and adapting the flat top edge of the main metal plate or strip 15 to be fixed direct to the outside face of a door.

My invention consists in the construction, arrangement, and combination of parts, as hereinafter fully set forth, pointed out in my claims, and illustrated in the accompanying drawings, in which—

Figure 1 is an inside face view of one end portion of the metal plate adapted to be fixed direct to a door and shows the relative positions of the operative parts connected therewith. Fig. 2 is a transverse sectional view on the line $\alpha\alpha$ of Fig. 1, showing the metal strip hinged to the bottom edge of the plate in its normal position. Fig. 3 is a transverse sectional view of the invention, showing it 25 fixed to the outside face of the bottom portion of a closed door and the hinged metal strip overlying the inclined face of the fixed threshold of the door as required in practical use. Fig. 4 is a perspective view of the lower portion of a door and an end portion of the fixed plate and hinged weather-strip in their relative positions when the door is open.

The letter A designates a strip of plate metal of uniform width from end to end. Its 30 top edge portion B is flat and straight and adapted to be fixed against the outside face of a door by means of nails or screws passed through perforations in said top edge portion. A double-elbow-shaped bend below the 35 flat top edge portion extending straight from end to end and a plurality of metal straps C, fixed to its inside face and coiled at their top ends to serve as bearings for a metal rod and bent inward at their lower ends to engage the 40 outside face of a door, adapt the lower portion of the plate and the metal straps to be

jointly fixed to the door by means of screws extended through coinciding perforations in the plate and straps and securely retained in position as required to provide space between 55 the plate and the door for operative devices that will be concealed and protected under the fixed plate A.

D represents a bell-crank lever pivoted to the inside face of the plate A, and F is a 60 metal rod extended through the coils at the upper ends of the fixed metal straps C, and its inner end is bent downward and pivotally connected with the short arm of the bell-crank lever D. Metal collars h are fixed to the 65 rod F and a contractile coil-spring placed on the rod and between the fixed collars in such a manner that the spring will normally retain the free end of the rod projected beyond the end of the plate A, as shown in Figs. 1 70 and 4.

A^2 is a straight strip of sheet metal inclined in opposite directions at its upper and lower edge portions and corresponding in length with the plate A. At some distance from the 75 lower edge and outside face are fixed hinges m, that are also fixed to the outside face and lower edge portion of the plate A, as shown in Figs. 2 and 3, in such a manner that the hinged strip can project upward when the 80 door is open, as shown in Figs. 2 and 4, or downward to overlie the threshold, as shown in Fig. 3. Straight pieces r of metal straps are jointly and pivotally connected with the bell-crank lever D and fixed to a hinge r' , 85 that overlies the inner face of the upper edge portion of the hinged strip A^2 , to which the hinge is fixed, as shown in Fig. 3, in such a manner that when the door is closed and the projecting end of the rod F comes in contact with the head of a screw s, adjustably fixed in the door-jamb, the coil-spring will be contracted and the bell-crank lever actuated as required to swing the hinged strip downward over the inclined face of the threshold, as 95 shown in Fig. 3, and when the door is opened the power stored in the contractile spring will be released and cause the hinged strip A^2 to swing upward into position, as shown in Figs. 2 and 4. By simply reversing the position of 100 the bell-crank lever and the movable rod and changing it from one end of the plate to the

other end it is obvious my weather-strip is adapted for use on right-hand and left-hand doors.

Having thus described the construction, application, and operation of my improved weather-strip, in which all the parts are made of metal and that is adapted to be advantageously combined with a door, the practical operation and utility of my invention will be readily understood by persons familiar with automatic weather-strips for doors.

What I claim as new, and desire to secure by Letters Patent, is—

1. In a weather-strip for doors, a plate bent into double-elbow shape from end to end at its upper edge portion and metal straps, coiled at their upper ends and bent at right angles at their lower ends, fixed to the inside face of the metal plate, as shown and described, for the purposes stated.
2. In a weather-strip for doors, a plate bent into double-elbow shape from end to end at its upper edge portion and metal straps, coiled at their upper ends and bent at right angles at their lower ends, fixed to the inside face of the metal plate, a rod extended through

said coils of the fixed metal straps, collars fixed to the rod and a coil-spring interposed between the collars, as shown and described, for the purposes stated.

3. An automatic weather-strip for doors comprising a metal plate bent into double-elbow shape from end to end at its top edge portion, metal straps having coils at their upper ends and elbows at their lower ends fixed to the inside face of the plate, a spring-actuated rod in the coiled ends of the fixed straps, a bell-crank lever pivoted to the inside face of the plate, a strip of metal hinged to the lower edge of the metal plate, at some distance from the edge of the strip, a hinge fixed to the edge of the strip, a metal link fixed to the hinge and pivotally connected with the bell-crank lever and a screw adjustably fixed in the door-jamb to engage the end of the spring-actuated rod, all arranged and combined to operate in the manner set forth for the purposes stated.

CHARLES A. ARMSTRONG.
